UNITED STATES PATENT OFFICE

140,429

DESIGN FOR A COVER CASING FOR A PICTURE PROJECTOR OR THE LIKE

Otto R. Nemeth, Chicago, Ill., assignor to Products Development, Inc., Chicago, Ill., a corporation of Illinois

Application December 23, 1944, Serial No. 117,052

Term of patent 14 years

(Cl. D61—1)

To all whom it may concern:

Be it known that I, Otto R. Nemeth, a National of Czechoslovakia, residing at Chicago, in the county of Cook and State of Illinois, have invented a new, original, and ornamental Design for a Cover Casing for a Picture Projector or the like, of which the following is a specification, reference being had to the accompanying drawings, forming part thereof.

Figure 1 is a side elevational view of a cover casing for a picture projector or the like, showing my new design, the opposite side being open.

Fig. 2 is a bottom plan view of the cover casing.

Fig. 3 is a top plan view of the cover casing.

Fig. 4 is an elevational view looking toward one end of the cover casing.

Fig. 5 is an elevational view looking toward the opposite end of the cover casing.

I claim:

The ornamental design for a cover casing for a picture projector or the like, substantially as shown and described.

OTTO R. NEMETH.
